TYPEWRITER CARRIAGE CONTROL MEANS
SUPPORTGiuseppe Prexios, Yverdon, Switzerland, assignor
to Paillard S. A., Sainte-Croix (Vaud), Switzerland, a corporation of SwitzerlandApplication June 8, 1949, Serial No. 97,818
In Switzerland June 25, 1948

6 Claims. (Cl. 197—186)

1

In the known typewriters, the controlling members for the various movements of the carriage, viz., the carriage advancing spring, the escapement mechanism for controlling the advancement of the carriage upon the depression of a character key or the spacing bar, the back-spacing mechanism, the margin counterstop means for limiting the movements of the carriage, the line-lock mechanism, the carriage release mechanism, the tabulating counterstop and the carriage brake as well as the bell mechanism are mounted on different parts of the frame of the machine.

As a result thereof, assembly is complicated and very often the aforementioned elements are accessible with great difficulties only because of the design of the machine.

The purpose of the present invention is to remedy these inconveniences by a design, in which all the controlling elements for the movement of the carriage are provided on a separable support attached to the frame of the typewriter and situated behind the carriage slide-rails.

One form of construction of the embodiment conforming to the present invention, is shown by way of example in the accompanying drawing, wherein:

Fig. 1 is a side elevation of the typewriter, partly sectioned;

Fig. 2 is a perspective view, on a larger scale, of the separable support carrying the controlling elements for the movement of the carriage, this view being taken from the inside of the typewriter.

On these drawings the separable support 1 carries the following elements: a spring drum 2 assuring in a known manner movement of the carriage as the keys are actuated, this movement being controlled by an escapement 3, the pinion 4 of which engages with the carriage-rack 5 fastened to the carriage 6.

The support 1 carries two projections 7 in which a stop 8 is pivoted and may perform a sliding motion against the pressure of a spring 9. This stop element engages with the margin-stops 10 (Fig. 1) for adjusting the length of the written line. In order to disengage the right hand margin-stop at the end of the line, the stop 8 is connected with a key of the keyboard controlling a connecting-rod 11 linked at 12 to an arm 13 of the stop 8. By operating the key of the keyboard, in the case of the stop 8 being engaged with the right hand margin-stop, the said stop 8 is pivoted between the projections 7 of the support so as to disengage the margin-stop and

to permit the typing of a certain number of letters.

The carriage 6 carries the displaceable stops 14 of the tabulator 15. In order to stop the movement of the carriage in a position fixed in advance, these stops engage with another stop 16 operated and actuated by a key 17 of the keyboard. This stop consists of the extremity of a sliding member 18, which, when the key 17 is operated, will protrude into the path of the displaceable stops 14 and at the same time will allow the movement of the carriage. To this effect a protruding part 19 of the sliding member 18 acts on one arm of a pivoted bent lever 20, the other arm of which, by means of its extremity 21, moves an oscillating support 22 of the carriage-rack 5 in such a manner as to disengage pinion 4.

The extremity 21 of the lever-arm 20 carries a braking element in order to slow down the movement of the carriage under the action of the advancing spring.

On the other hand, the support 1 carries the device provided for back-spacing of the carriage against the action of the advancing-spring 2. This device consists of a lever 19 actuated by a connecting rod 20 by means of a key on the keyboard. By its action, the escapement-wheel 3 is rotated in a direction opposite to the one corresponding to the advancement of the carriage 6.

The keys employed for disengaging the carriage as well as for the return movement of the same, are provided on the key-board, as is the case with the key 17.

At the end of the written line, the striking of the type-bars is prevented by a locking device constituted by an arm 21 of the oscillating part 22 of the escapement carrying the pawls 23.

The part 22 is operated not only by the spacing-bar 24 of the keyboard by means of the connecting-rod 25 actuating the lever 26, but also by means of the universal rail 27 of the type-bars 28. The rail 27 is fulcrumed at 29 and 30 on two oscillating levers 31 and 32, the last mentioned of which is connected to the arm 34 of the oscillating part 22 by means of a rod 33.

The locking of the escapement at the end of the written line is obtained in the following manner:

While writing, before reaching the end of the line, the arm 21 oscillates freely at the same time as the oscillating part 22 of the escapement. At the end of the line, the right-hand margin-stop engages with stop 8 and moves the same from right to left against the pressure of the spring 9.

On the support 1 is pivoted a lever 39, the protruding part 40 of which, under the action of spring 43, is in contact with a protruding part 41 of the stop 8 and which is also provided with another protruding part 42 intended to intersect the path of arm 21.

In the course of the movement from right to left of the aforementioned stop 8, the protruding part 41 liberates the lever 39 which, under the action of the spring 43 oscillates and places its 10 bent extremity 42 in the path of the lever 21, thus blocking the escapement.

On the back face of the support 1 is fastened a bell 44, the hammer 45 of which is actuated by a projection 46 (Fig. 1) of the margin-stop 15 against the action of spring 47. On its passage, the projection 46 touches the part 48 of the hammer.

The support 1 may be fastened to the frame of the typewriter by means of ordinary screws. The 20 connection between the support and the frame may be of the resilient type in order to dampen the shocks transmitted from the carriage to the various elements which it carries and to decrease, by this means, the noise.

The placing of all the members controlling the movement of the carriage on a single and movable support fastened in the freely available space of the machine-frame, behind the slide-rails of the carriage, results in a great facility 30 for assembling the typewriter.

I claim:

1. In a typewriter including a carriage, the combination comprising a stationary frame including slideways for the carriage, a detachable support affixed to the frame behind the slideways, yieldable means mounted on the support and urging the carriage to a predetermined position, an escapement mechanism mounted on the support and controlling the advancement of the carriage, a back-spacing mechanism mounted on the support, margin counterstop means mounted on the support and limiting the movement of the carriage, a line lock mechanism mounted on the support, a carriage release mechanism mounted on the support, tabulating counterstop means mounted on the support, carriage brake means mounted on the support and operable simultaneously with the carriage release mechanism, and bell means mounted on the support.

2. The combination according to claim 1 and wherein the carriage release mechanism is operable simultaneously with the operation of the tabulating counterstop means.

3. The combination according to claim 1 and wherein the carriage release mechanism includes an arm and the tabulator counterstop means when operated swings the arm to release the carriage, said arm braking the carriage upon release thereof.

4. The combination according to claim 1 and

wherein the margin counterstop means includes a stop pivoted to the support and slidably urged to a predetermined position.

5. The combination according to claim 1 and wherein the margin counterstop means includes a stop pivoted to the support and slidably urged to a predetermined position, and the escapement mechanism includes an arm, said combination also comprising a lever fulcrumed to the support and urged to a predetermined position and normally held in a second position by the margin counterstop means when in its predetermined position, said lever moving to its predetermined position and in the path of the arm upon movement of the margin counterstop means by the carriage margin stop from its predetermined position to thereby lock the escapement mechanism and prevent motion of the carriage.

6. In a typewriter including a carriage, the combination comprising a stationary frame, a support on the frame, yieldable means urging the carriage to a predetermined position and mounted on the support, an escapement mechanism mounted on the support and controlling the advancement of the carriage and including a swingable part carrying an arm, back-spacing mechanism mounted on the support, margin counterstop means mounted on the support and limiting the movement of the carriage and including a stop pivoted to the support and slidably urged to a predetermined position, a line lock mechanism mounted on the support, a carriage release mechanism mounted on the support, tabulating counterstop means mounted on the support, carriage brake means rigid with the carriage release mechanism and mounted on the support, bell means mounted on the support, and a lever fulcrumed on the support and urged to a predetermined position and normally held in a second position by the margin counterstop means when in its predetermined position, said lever moving to its predetermined position and in the path of the arm upon movement by the carriage margin stop of the margin counterstop means from its predetermined position to thereby lock the escapement mechanism and prevent motion of the carriage.
